Primary Examiner — Cynthia Underwood(74) *Attorney, Agent, or Firm* — McHale & Slavin, PA(57) **CLAIM**

The ornamental design for a wall mounted hose hanger, as shown and described.

DESCRIPTION

FIG. 1 is a top right perspective view of the wall mounted hose hanger of the present invention;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a top left perspective view thereof.

The portions of the wall mounted hose hanger illustrated in broken lines form no part of the claimed subject matter.
